LOGGING CONVEYER

William E. McCraw, Bishops Falls, Newfoundland

Application September 1, 1936, Serial No. 98,996

1 Claim. (Cl. 198—115)

This invention relates to an apparatus for mechanically browsing pulpwood and a suitable construction is set forth in the following description and illustrated in the accompanying drawings, in which,

Fig. 1 is a side elevation of a browsing machine constructed in accordance with the invention.

Fig. 2 is a detail view of the means for elevating or lowering the sections.

10 Fig. 3 is a detail view showing part of the driving mechanism.

Fig. 4 is a plan view of the power drive.

Fig. 5 is a cross section on the line 5—5, Fig. 4, showing in addition part of the conveyer.

15 Fig. 6 is a cross sectional view of the conveyer belt on the line 6—6, Fig. 1.

Fig. 7 is a fragmentary side elevation of the conveyer belt.

Like characters of reference refer to like parts 20 throughout the specification and drawings.

The brows consists of five movable conveyer sections 11, 12 and 13 which are each six feet long and 14 and 15 which are five feet long. Each section is pivotally connected to the adjacent section and the middle section 13 is pivotally mounted on the frame work 16 so that it can be brought up or down. The framework 16 is pivotally mounted on the frame 17, which is mounted on the vehicle having tractor treads 18.

25 This design of the sections of the brows allows the sawn pulpwood to be delivered to the brow at various heights as shown by the five positions, A5, B5, C5, D5 and E5. It will be noted from this construction that in moving the brows from

30 one position to another that sections 15 and 14 can be folded back on section 13 and section No. 11 can be folded back on section No. 12, and 13 lowered to rest on its bearing formed by the framework 16. This makes a very compact ar-

40 rangeement for transporting.

In operation, the brows works across the supporting frame and is swung lengthwise for moving. The framework 16, upon which the section 13 is mounted, forms a turntable which is pivotally mounted on the axis 19.

45 The brows is powered by belt or chain drive from the front power take off of the tractor used in skidding. For this purpose, the brows is provided with a driven pulley 20 which, through a suitable arrangement of gears, drives the conveyer heretofore described.

50 In Figs. 4 and 5 is shown the means for driving the conveyer 21 and this consists of the pulley 20 and gear box 22 which houses a suitable train

of gears 23 for reducing the speed of rotation. The gear train 23 drives the shaft 24 which is provided with a bevelled gear 25. Housed in the axis 19 is a driven shaft which is provided at its lower end with a bevelled gear 26 meshing with the gear 25. The upper end of the last mentioned shaft is provided with a bevelled gear 27 which meshes with a bevelled gear 28 mounted on the frame 16. The shaft 29 on which the gear 28 is mounted is provided with a pulley over which the belt 30 passes. The belt 30 drives a pulley wheel 31 over which the conveyer belt 21 passes. The means for adjusting the height of the conveyer to positions A5, B5, C5, D5 and E5 shown in Fig. 1 consists of a cog-wheel 32 which is mounted on the shaft 33, the shaft 33 pivotally connecting the adjoining ends of the several sections forming the conveyer. In the construction shown, the cog-wheel 32 is so mounted or connected to the section 15 that upon rotation of 20 the cog-wheel 32 clockwise, the section 15 will be raised and upon rotation in the opposite direction, section 15 will be lowered. Meshing with each cog-wheel is a cog-wheel 34 which is mounted on the end of the section adjoining the 25 one to which the cog-wheel 32 is connected. The cog-wheel 34 is rotated by a crank 35 and is locked by a pawl 36.

In operation, the sawn pulpwood lengths are carried direct from the sawing machine and 30 placed on the apron or section 11 of the brows, the brows having been adjusted first to the correct elevation. The brows delivers sawn pulpwood to the brow where it is piled in blocks.

Having thus fully described my invention what 35 I claim as new and desire to secure by Letters Patent is:

A mechanical brows comprising a framework supported on a carriage, a turntable mounted on said framework, a movable conveyer formed of a 40 plurality of sections mounted on said turntable, one of said sections being hinged to said turntable for vertical movement, a shaft pivotally connecting each section to an adjacent section permitting each section to be swung on said shaft 45 to different positions and means carried by each section for moving the same to different positions comprising a cog wheel carried by each shaft and attached to the end of one section, a second cog wheel meshing therewith carried by the adjoining 50 section, a crank for rotating said second cog wheel and a pawl engaging with said second cog wheel.

WILLIAM E. McCRAW,
